UNITED STATES PATENT OFFICE.

ALBERT J. SMART, OF GREENFIELD, MASSACHUSETTS, ASSIGNOR TO
WILEY & RUSSELL MANUFACTURING COMPANY, OF GREENFIELD,
MASSACHUSETTS, A CORPORATION OF MASSACHUSETTS.

SCREW-THREADING DIE.

SPECIFICATION forming part of Letters Patent No. 777,442, dated December 13, 1904.

Application filed April 13, 1904. Serial No. 203,002. (No model.)

To all whom it may concern:

Be it known that I, ALBERT J. SMART, a citizen of the United States, residing at Greenfield, in the county of Franklin and State of Massachusetts, have invented certain new and useful Improvements in Screw - Threading Dies; and I do hereby declare the following to be a full, clear, and exact description of the invention, such as will enable others skilled in the art to which it appertains to make and use the same.

This invention relates to screw-threading dies, more particularly to what are known as "divided" dies, which allow of adjustment to compensate for wear or to cut screws of different depths and sizes by means of a single die and also render repairing and sharpening easier; and the objects of the present invention are to construct a more compact, strong, and solid divided die for performing the functions above described and to obviate many of the objections which have heretofore been found to exist in dies of this class.

Further objects of the invention will hereinafter appear; and to these ends the same consists of a screw-threading die for carrying out the above objects embodying the features of construction, combination of elements, and arrangement of parts substantially as hereinabove fully described and claimed in this specification and shown in the accompanying drawings.

While the essential and characteristic features of the invention are susceptible of modification, still the preferred embodiment thereof is illustrated by the figures of the drawings, in which—

Figure 1 is a plan view of the die. Fig. 2 is a sectional view of the die through the adjusting and connecting means. Fig. 3 is a sectional view on the line 3 3 of Fig. 2, showing the construction of the cone adjustment. Fig. 4 is a sectional view on the line 4 4 of Fig. 2, showing the construction of the hinged connection; and Fig. 5 is an enlarged detail of the recesses in the separable parts of the die forming a part of the hinged connection.

Referring to the drawings, *a* and *b* repre-

sent the two halves of a divided die formed, preferably, of hardened steel, being provided, as usual, on their inner faces with threads *c*, forming when put together a female screw for cutting threads. The size of this female screw is adjustable by the means hereinafter described, which consist, essentially, of a hinged connection for holding the halves *a* and *b* together and located substantially entirely within the material forming the die in combination with an arrangement of cones, also substantially entirely within the material forming the die adapted to separate the halves *a* and *b* and swing them either apart or together on the hinged connection.

As shown more particularly by Figs. 4 and 5, the hinged connection is preferably formed by providing recesses *d* on both the upper and lower sides of lugs *e*, left upon the surface of one pair of meeting ends of the two halves. Between these lugs is interposed a double-headed screw-shank *f*, having preferably one head in the form of a nut and one or both of said heads being cup-shaped. In the drawings both heads are shown cup-shaped, so as to fit in the double pair of recesses also there shown. The cup-shaped portion of head *g* fits snugly in the pair of recesses *d* on one side of the lugs *e* and the cup-shaped portion of nut *h*, which nut is preferably of similar proportions to head *g*, fits snugly in the pair of recesses *d* on the opposite side of lugs *e*. It will be readily seen that such a construction forms an exceedingly compact and efficient hinge-joint, which may be made tight or loose at will and always accessible. The adjusting means (shown more particularly by Fig. 3) consist of a screw-shank *i*, provided with a conically-formed head *j* and leading into a nut *k* in the form of a conical frustum, the whole being interposed between the pair of meeting ends of the halves of the die opposite the hinge connection, the conically-formed head *j* and nut *k* fitting snugly into recesses *l*, formed in said meeting ends and constructed to receive them. This construction also allows access by the workman under all conditions.

The advantages of such a construction are manifest, as it forms a die standing complete in itself and entirely does away with the necessity of the "guide" or "collet," which had to be used in former constructions of an adjustable divided die, and under any adjustment the die is held firmly by a pressure evenly distributed upon both the upper and lower edges, keeping them perfectly firm, 5 to solid, and true, which is absolutely necessary to cut perfect threads.

To adjust the die, the halves *a* and *b* are turned upon the hinged connection or pivotal point formed by turning down the screw-head 10 *g* and drawing it and the nut *h* into engagement with the recesses *d*, formed in the lugs *e*. To adjust for wear, the taper-headed screw *i* is then withdrawn, forcing the tapered nut *j* outwardly, and the halves *a* and *b* are pressed 15 together, while to adjust to cut a screw-thread of larger diameter said screw *i* is forced inward, drawing the said nut *j* also inward and forcing the halves *a* and *b* apart. The adjustment is sure, accurate, and permanent.

20 It should be understood that this die may be held in any way that a solid die may be held, and therefore may be used with any form of die-holder, either a die-stock for hand working or a chuck for machine-work, or 25 adapted to be used in a bit-brace. As the holder does not form a part of this present invention, it is not deemed necessary to illustrate the die in combination therewith.

Obviously some features of this invention 30 may be used without others, and the invention may be embodied in widely varying forms.

Therefore, without limiting the invention to the construction shown and described nor enumerating equivalents, I claim and desire 35 to obtain by Letters Patent the following:

1. In a divided die for cutting screw-threads connecting means comprising a double-headed shank, one of said heads being cup-shaped, and means on the die parts with which said

head is adapted to engage, substantially as described. 45

2. In a divided die for cutting screw-threads, connecting means comprising a shank provided with an integral and a movable head, one of said heads being cup-shaped, and means 50 on the die parts with which the cup-shaped head is adapted to engage, substantially as described.

3. In a divided die for cutting screw-threads, a hinge between the die parts consisting of a 55 cup-headed screw having a cup-shaped nut threaded thereon, and recessed lugs on the die parts with which said members are adapted to engage, substantially as described.

4. In a divided die for cutting screw-threads, 60 a hinged connection comprising two cup-shaped members, means on said die parts with which said members are adapted to engage, and connecting means adapted to hold said members in place, substantially as described. 65

5. In a divided die for cutting screw-threads, a hinged connection comprising a recessed lug on each of said die parts, two cup-shaped members constructed to engage with said recesses, and connecting means adapted to hold said 70 cup-shaped members in place, substantially as described.

6. In a divided die for cutting screw-threads, a hinged connection comprising a lug on each of said parts provided with recesses on each 75 side thereof, a screw-shank between said lugs having a cup-shaped head constructed to engage with the recesses on one side and a cup-shaped nut on said screw-shank constructed to engage with the recesses on the other side, 80 substantially as described.

In testimony whereof I affix my signature in presence of two witnesses.

ALBERT J. SMART.
